UNITED STATES PATENT OFFICE

GEORGES HURET, OF PARIS, FRANCE, ASSIGNOR TO SOCIETE ANONYME JEAN PATOU, OF PARIS, FRANCE, A CORPORATION OF FRANCE

DESIGN FOR A BOTTLE

Application filed April 16, 1929. Serial No. 30,917. Term of patent 7 years.

To all whom it may concern:

Be it known that I, GEORGES HURET, a citizen of the Republic of France, residing in the city of Paris, France, have invented a new, original, and ornamental Design for Bottle, of which the following is a specification, reference being had to the accompanying drawing, forming a part thereof.

In the drawing—

Fig. 1 is a perspective view of my bottle, and

Fig. 2 is a side view thereof.

I claim:

The ornamental design for a bottle as shown.

GEORGES HURET.
